UNITED STATES PATENT OFFICE

MICHAEL J. FOLEY, OF GREENFIELD, MASSACHUSETTS, ASSIGNOR TO GREENFIELD TAP & DIE CORPORATION, OF GREENFIELD, MASSACHUSETTS, A CORPORATION OF MASSACHUSETTS

DIE HOLDER

Application filed July 24, 1929. Serial No. 380,709.

This invention relates to a holder for dies used in cutting screw-threads on pipes, rods or other similar work.

It is the object of my invention to provide a die-holder so constructed that cutting dies of more than one size or dimension may be effectively secured therein.

A further object is to provide improved means for adjusting the cutting dies in the holder to cut a thread of the exact required size, and to provide means for firmly securing the cutting dies in adjusted position in said holder.

My invention further relates to arrangements and combinations of parts which will be hereinafter described and more particularly pointed out in the appended claims.

A preferred form of the invention is shown in the drawings in which

Fig. 1 is a plan view of my improved holder with a pair of cutting dies mounted therein;

Fig. 2 is a similar view but showing dies therein formed of a different width of blank;

Fig. 3 is a plan view of the holder without the dies;

Fig. 4 is a sectional elevation, taken along the line 4—4 in Fig. 1;

Fig. 5 is a sectional elevation of a clamping member;

Fig. 6 is a bottom view thereof;

Fig. 7 is a detail sectional elevation, taken along the line 7—7 in Fig. 1; and

Fig. 8 is a perspective view of one of the cutting dies.

Referring to the drawings, my improved die-holder comprises a cylindrical member or disc 10 adapted to be mounted in a die-stock 11, shown in dotted lines in Fig. 4, and to be secured therein by a binding screw 12. The die-holder 10 is provided with undercut openings in one face thereof forming guideways 14 and 16 for cutting dies 18 (Fig. 2) or 20 (Fig. 1).

It will be noted that the guideways 14 are relatively narrow, to fit the narrower blanks from which the cutting dies 18 are formed, while the guideways 16 are relatively wide, to receive the wider blanks from which the cutting dies 20 are formed.

Adjusting screws 22 are threaded in the die-holder 10 in alignment with the guideways 14 and 16, and serve for adjusting the cutting dies toward the axis of the die to the exact required position.

The lower part of the die-holder is provided with a large internally-threaded opening 24, which receives a threaded clamping plate 26. The plate 26 is provided with a central opening 27 to clear the work and with openings 28 for application of a wrench or spanner.

When the plate 26 is screwed firmly into the opening 24 and against the under sides of the cutting dies 18 or 20, the dies are forced upward into the undercut guideways 14 or 16 and are thus held firmly in position.

Index lines 30 may be provided on the holder 10 and cutting dies 18 or 20, by which the dies may be quickly and easily adjusted to the desired position.

In the manufacture of screw-cutting dies of this general type, it is customary to cut the threads of different diameters in blanks of different widths. By the use of my improved holder, it is necessary to provide only one half as many holders as there are sizes of die blanks and each size die may be conveniently adjusted and will be accurately held in said holder.

Having thus described my invention and the advantages thereof, I do not wish to be limited to the details herein disclosed, otherwise than as set forth in the claims, but what I claim is:

1. A die-holder comprising a body having a pair of oppositely disposed undercut guideways of one width formed therein and having a second pair of oppositely disposed undercut guideways of a different width formed therein, and means to hold a pair of cutting dies of one width of stock in one pair of said guideways or a pair of cutting dies of a different width of stock in the other pair of said guideways said two pairs of dies being 90 slidably in said guideways along lines perpendicular to the same work axis.

2. A die-holder comprising a body having a pair of oppositely disposed undercut guideways of one width formed therein and hav-

- ing a second pair of oppositely disposed undercut guideways of a different width formed therein, said second pair of guideways being disposed substantially perpendicular to said 5 first pair, and means to hold a pair of cutting dies of one width of stock in one pair of said guideways or a pair of cutting dies of a different width of stock in the other pair of said guideways.
- 10 3. A die-holder comprising a body having a pair of oppositely disposed undercut guideways of one width formed therein and having a second pair of oppositely disposed undercut guideways of a different width formed 15 therein, and a single clamping element for all of said guideways effective to hold a pair of cutting dies of one width of stock in one pair of said guideways or a pair of cutting dies of a different width of stock in the other 20 pair of said guideways.
4. A die-holder comprising a body having a pair of oppositely disposed undercut guideways of one width formed therein and having a second pair of oppositely disposed undercut guideways of a different width formed 25 therein, means common to all of said guideways to hold a pair of cutting dies of one width of stock in one pair of said guideways or a pair of cutting dies of a different width 30 of stock in the other pair of said guideways, and separate means to adjust each cutting die radially in said holder.

In testimony whereof I have hereunto affixed my signature.

35 MICHAEL J. FOLEY.
